Primary Examiner — Bridget L Eland(74) *Attorney, Agent, or Firm* — Stephen C. Beuerle;
Procopio Cory Hargreaves & Savitch LLP**CLAIM**

The ornamental design for a laryngoscope handle, as shown and described.

DESCRIPTION

FIG. 1 is a perspective view of the laryngoscope handle.

FIG. 2 is a left side elevational view of the laryngoscope handle.

FIG. 3 is a right side elevational view of the laryngoscope handle.

FIG. 4 is a rear elevational view of the laryngoscope handle.

FIG. 5 is a front elevational view of the laryngoscope handle.

FIG. 6 is a top plan view of the laryngoscope handle; and,

FIG. 7 is a bottom plan view of the laryngoscope handle.

The broken lines immediately adjacent the claimed areas represent the bounds of the claimed design while all other broken lines are directed to environment and are for illustrative purposes only; the broken lines form no part of the claimed design.
